UNITED STATES PATENT OFFICE.

OSCAR W. SODERSTROM, OF NEW YORK, N. Y., AND WARREN FUHRMANN, OF WESTFIELD, NEW JERSEY.

BUTTON-MACHINE.

1,305,570.

Specification of Letters Patent. Patented June 3, 1919.

Application filed March 2, 1917. Serial No. 151,965.

To all whom it may concern:

Be it known that we, OSCAR W. SODERSTROM, a citizen of the United States, and a resident of New York city, county of Bronx, and State of New York, and WARREN FUHRMANN, a citizen of the United States, and a resident of Westfield, county of Union, and State of New Jersey, have invented certain new and useful Improvements in Button-Machines.

This invention has for its object to provide improved mechanism for sawing slots in the opposite sides of an article, while the article is held stationary, and the saws are caused to approach and recede from the article while they are being rotated; the article being held between the saws to be operated upon on opposite sides thereof. The invention is practically designed for use in a machine for automatically producing buttons or fasteners of the type known as resilient head and socket; in which devices a head of the socket member is formed by dies on a strip of sheet metal, and has slots cut in the opposite sides of the head near the base, while the heads are a part of a continuous strip, and later disks each containing a head are blanked out and formed into the button shape.

30 A further object of the invention is to provide in connection with such mechanism, means for supporting or holding the blank and head against displacement during the operation of the saws.

35 In the accompanying drawing is shown the invention as applied to a button machine of the kind set forth, Figure 1 is a plan view of the mechanism. Fig. 2 is a vertical longitudinal section. Fig. 3 is a transverse section on the line 3—3 of Fig. 4; and Fig. 4 is a front elevation.

As shown in the drawing, we provide a bed 20, and a plunger 21 movable to and from the bed by suitable means not herein set forth. Means are provided for supporting, and also for preferably feeding a blank or strip 22. The slotting means comprises circular saws 26 and 27 rotated by arbors 28 and 31 that are journaled in slides 29 and 32. The latter are movable transversely of the bed in guideways 30, whereby to engage an article suitably supported at 49 on the bed. For the purpose of continuously rotating the saw arbors during the said reciprocation of the slides, we provide

a cross-shaft 34 rotatable in bearings in the slides 32 and 29, as shown in Fig. 3. The saw arbors 28 and 31 have miter gears 36 and 37 secured to their lower ends, which gears mesh with miter gears 38 and 39 respectively, on the shaft 34. These gears on the shaft are splined thereon to permit them to slide a short distance on the shaft, yet be rotated thereby. On driving the shaft by a pulley 35, driven from a suitable source of power by a belt, the meshing pairs of gears will cause continuous rotation of the saws, during the reciprocation of the carriers.

Means are provided for causing the approach and recession of the carriers and saws to engage the article on opposite sides, which means is preferably connected with the plunger 21. Cam arms 41 and 42 on the plunger engage cam faces 43 and 44 on the carriers 29 and 32 respectively, and cause approach of the carriers on descent of the plunger, whereby the article will be slotted. On retraction of the cam arms by the plunger, the carriers are retracted to former position to separate the saws, by a coil spring 40 on the shaft 34. This spring is compressed when the carriers approach, and will force them apart when the plunger goes upward. A bracket 45 serves to prevent endwise movement of the shaft during movement of the carriers.

The blank strip 22 may be advanced between each descent of the plunger by suitable feeding means such as rolls 13 and 14, the latter having a gear 15 engaged by a pawl 16 on an arm 17. The latter is swung by a bar 18 on the plunger, and retracted by a spring 19, so that when the plunger moves upward the pawl will turn the roll 14 to feed the strip 22. This strip may have the heads formed thereon by suitable dies 23 and 24, whereby the finished heads 1 are provided on the strip. The strip is advanced at each retraction of the plunger, a sufficient distance to bring the next head to the place 49 on the bed, where it is engaged by the saws when advanced, and slots cut in the opposite sides of the head.

Means are further provided for holding the strip and head to prevent displacement by the engagement of the saws, and which means further serve to accurately position the strip and head for such operation. A spring punch or block is provided on the 110

plunger 21. As shown a block 7 slides in a bore 8 in the plunger, and is pressed downwardly by a spring 9 that engages a plug 10 in the bore. The bore has a shoulder 11, en-
5 gaging the enlarged extremity of the block to limit the downward movement when free. The lower end of the block has a part spherical cavity 12 curved to fit the head, and the block is preferably beveled on its two lat-
10 eral sides. It will be understood that this block engages only the upper portion of the head, that is, above the portion engaged by the saws, near the base of the head on the strip.

15 From this construction it will be understood that each time the plunger descends the saws will move inwardly and cut slots in the opposite sides of any article placed therebetween, such as the heads on the strips.

20 When the plunger descends the cavity 12 in the block 7 will first engage the head to center it and hold it against lateral displacement. The block having a resilient connection, engages the head before operation of
25 the saws, and it recedes into the plunger on continued downward movement to advance the saws. When the plunger is retracted, the saws will be moved back by the coil spring acting on the carriers. The continu-
30 ous rotation of the shaft 34 will cause the saws to be revolved during the approach and recession of the saws. Heretofore slots in heads of this character have been cut by a pair of saws on stationary arbors, with the
35 heads on the strip drawn through or between the saws. This produced a strain on the strip and the head, causing bending and distortion of the strip, and also resulted in unequal slots being formed. The present in-
40 vention obviates this difficulty, by having the strip and head stationary and held firmly in a fixed position, while the saws are brought up to engage the head and then caused to recede.

45 Having thus described our invention, what we claim is:-

1. The combination with a bed adapted to support an article, of a pair of carriers mounted to reciprocate on the bed on oppo-
50 site sides of the article, a circular saw on each carrier, means for reciprocating the carriers to bring the saws to engage the article on opposite sides, including yieldable means for moving the carrier in one direc-
55 tion, and means for continuously rotating the saws during such movement of the carriers.

2. The combination with a bed adapted to support an article, of a pair of carriers mounted to reciprocate on the bed on oppo-
60 site sides of the article, a circular saw on each carrier, means for sliding the carriers to bring the saws to engage the article on opposite sides, a driving shaft extending across
65 the bed, a miter gear connected with each

saw arbor, a pair of miter gears slidably splined on said shaft and engaging said saw gears respectively and means interposed between the gears on the shaft for sliding the carrier away from the article.

3. The combination with a bed adapted to support an article, of a pair of carriers mounted to reciprocate on the bed on oppo-
70 site sides of the article, a circular saw on each carrier, means for advancing the carriers to bring the saws to engage the article on opposite sides, a driving shaft extending across the bed, a miter gear connected with each saw arbor, a pair of miter gears slidably splined on said shaft and engaging
75 said saw gears respectively, and a coil spring on the shaft for retracting the carriers when advanced.

4. In a button machine, the combination with a bed adapted to support an article, and a plunger movable to and from the bed, of a pair of carriers mounted to reciprocate on the bed on opposite sides of the article, a circular saw on each carrier, cam arms on the plunger arranged to reciprocate the carriers to bring the saws to engage opposite sides of the article, and a driving shaft on the bed arranged to rotate the saws during
80 said movement of the carriers.

5. In a button machine, the combination with a bed adapted to support an article, and a plunger movable to and from the bed, of a pair of carriers mounted to reciprocate on the bed on opposite sides of the article, a circular saw on each carrier, cam 95 arms on the plunger arranged to advance the carriers to bring the saws to engage opposite sides of the article, a driving shaft on the bed arranged to rotate the saws during
100 said movement of the carriers, and a coil spring on the shaft to separate the carriers on retraction of the plunger.

6. In a button machine, the combination with a bed adapted to support an article, and a plunger movable to and from the bed, of a pair of carriers mounted to reciprocate on the bed on opposite sides of the article, a circular saw on each carrier, a driving shaft extending across the bed, a miter gear connected with each saw arbor, a pair of miter
115 gears slidably splined on said shaft and engaging said saw gears respectively, a coil spring on the shaft arranged to separate the carriers when advanced, and cam arms on the plunger arranged to engage the carriers 120 respectively to advance the carriers to cause approach of the saws.

7. In a button machine, the combination with a bed adapted to support a strip having heads, of a pair of carriers mounted to reciprocate on the bed on opposite sides of the strip, a circular saw on each carrier, means for reciprocating the carriers to bring the saws to engage a head on the strip on opposite sides to cut slots in the head,
125 130

means for rotating the saws during the movement of the carriers, and means to engage the head on the strip during the operation of the saws on such head.

8. In a button machine, the combination with a bed adapted to support a strip having heads, and a plunger movable toward and from the bed, of a pair of carriers mounted to reciprocate on the bed on opposite sides of the strip, a circular saw on each carrier, means for reciprocating the carriers to bring the saws to engage a head on the strip on opposite sides to cut slots in the head, means for rotating the saws during the movement of the carriers, and a block on the plunger arranged to engage the head during the operation thereon by the saws.

9. In a button machine, the combination with a bed adapted to support a strip having heads, and a plunger movable toward and from the bed, of a pair of carriers mounted to reciprocate on the bed on opposite sides of the strip, a circular saw on each carrier, means for reciprocating the carriers to bring the saws to engage a head on the strip on opposite sides to cut slots in the head, means for rotating the saws during the movement of the carriers, and a block on the plunger arranged to engage the

head during the operation thereon by the saws, said block having a resilient connection with the plunger.

10. In a button machine, the combination with a bed adapted to support a strip having heads, and a plunger movable toward and from the bed, of a pair of carriers mounted to freely reciprocate on the bed on opposite sides of the strip, a circular saw on each carrier, means controlled by the plunger for reciprocating the carriers to bring the saws to engage a head on the strip on opposite sides to cut slots in the head, and means for rotating the saws during the movement of the carriers.

11. In a button machine, the combination with a bed adapted to support a strip having heads, and a plunger movable toward and from the bed, of a pair of carriers mounted to freely reciprocate on the bed on opposite sides of the strip, a circular saw on each carrier, means connected with the plunger for advancing the carriers to bring the saws to engage a head on the strip on opposite sides to cut slots in the head, means for rotating the saws during the movement of the carriers, and a spring to retract the carriers when the plunger is retracted.

OSCAR W. SODERSTROM.
WARREN FUHRMANN.
